PORTABLE CAMPING SINK

Jack C. Leavitt, Independence, Oreg., assignor of
fifty per cent to Ernest E. Bechtelheimer, As-
toria, Oreg.

Application October 6, 1949, Serial No. 119,879

4 Claims. (Cl. 4—187)

1

This invention relates to portable camping equipment and more particularly to a portable sink which is constructed so that it includes all of the customary features and advantages of a rigid-type sink or tub connected to a supply conduit.

The primary object of this invention is to provide a sink or tub that may be transported and set up at any desired spot, the sink, when set up, having its own supply of running water.

Another important object of this invention is to provide a simple, compact and inexpensive sink which includes a tank section and a tub section hingedly connected thereto, means being provided for locking the sections together in unitary fashion so that they may be easily carried, and means being provided for supporting the sections in an open, operative relationship.

These and ancillary objects are attained by this invention, the preferred embodiment of which is set forth in the following description and illustrated in the accompanying drawings, wherein:

Figure 1 is a top plan view of the portable sink taught by this invention, the same being illustrated in an open, operative position;

Figure 2 is a longitudinal sectional view taken on line 2—2 of Figure 1;

Figure 3 is a transverse sectional view taken on line 3—3 of Figure 2;

Figure 4 is a rear elevational view;

Figure 5 is a detailed sectional view taken on line 5—5 of Figure 3;

Figure 6 is an enlarged sectional view taken on line 6—6 of Figure 2 and illustrating the means for retaining the tank and base sections in open, operative relationship;

Figure 7 is an end elevational view of the sink in a closed position; and

Figure 8 is a front elevational view of the sink in a closed position.

In the accompanying drawings, the sink, generally designated by the character reference 10, includes a pair of casings or members 12 and 14, which are hingedly secured together. The casing 12 is a substantially rectangular, box-like member, which defines a tank, and the member 14 includes a bottom wall 16 having opposed upstanding side and end walls 18 and 20. The top or inner portion of the section is open and the tank 12 is secured by hinges 21 to one of the sides 18 of the casing 14. A filling aperture is formed in the outer side wall 22 of the tank 12 and a closure member 24 is threaded in the aperture. A conventional swivel faucet 29 is secured in the lower portion of the inner side wall 28 of the tank, and means is provided for supporting the tank in perpendic-

2

ular relation to the member 14 so that the faucet 26 overlies the upper open side of the section 14. In this respect, it is to be noted that a rectangular rim 30 is formed on the inner surface of the side and end walls 18 and 20, with a center web 32 positioned transversely between the sides of the rim to receive and retain against lateral movement of basins 34. A supporting bar 33 extends longitudinally between the end walls 20 and is disposed below and transversely to the web 32. Receptacles or basins 34 and 36 having laterally disposed peripheral flanges 38 are provided, the receptacles being disposed in the adjacent openings defined by the ribs and suspended in the casing 14 by means of the flanges 38 on the upper edges thereof, which are seated on the rim and web thereof and the bottom walls resting on the bar 33, as seen in Figure 1.

A pair of supporting arms 40 and 42 are pivotally secured to projecting apertured ears 44 formed on the inner side walls 28 of the tank and are formed with unattached opposing ends 46 terminating in extending tongues or fingers 48. Inclined openings 50 are formed in the opposing ends of the rim 30 and the free ends 46 of the bars are seated therein, as seen in Figure 6, whereby the tank is locked in right angular relation to the casing 14 and extends perpendicular from the side wall 18 to seat on supporting plates 51 vertically mounted on the outer wall 18.

A supporting shelf 52 is provided and is adapted to be attached to one of the end walls 20 of the casing 14, when the two members are in open relationship and the sink is set up for use. The shelf 52 may be formed on its upper face with longitudinal drain ribs or the like, if desired. As seen in Figure 2, a brace arm 54 is pivotally secured, as at 56, to a downwardly extending apertured ear 58 which is formed on the under face of the shelf. A reduced finger 60 extends from the opposing end of the bar and is inserted through an opening 62 in the wall. Lugs 64 are formed on the inner end of the shelf and are adapted to be detachably received within openings 66 formed in the end wall 20, adjacent the upper edge thereof, so that the shelf is supported in a horizontal plane and extends outwardly from the end wall 20, adjacent the upper edge thereof.

Means is provided for heating the water within the tank 12 and includes a plurality of U-shaped heating tubes 68, the lower unattached ends of the tubes being seated in the side wall 70 of the tank and the upper ends being supported by rods 72 secured to the wall 22 of the tank. A burner 74 is mounted below the open ends of the tubes by means of a bracket 76. A fluid receptacle

or tank 78 is supported by clamps 80 and attached thereby to angle members 82 depending from the side wall 18 of the casing 14. A connection 84 is formed between the burner and the tank or a cylindrical receptacle, so that kerosene or similar fluid stored by the tank 78 is fed to the burner 74. It is to be noted that the burner is in vertical alignment with the heating tubes, when the tank is in a vertical position, so that the heating tubes are heated by the burner and the water in the tank is thus heated for use.

Means is provided for locking the tank and casing together in closed relation for carrying purposes and for supporting the casing in a raised horizontal position. The means includes a pair of U-shaped supporting standards 86 and 88 which are pivotally secured to transversely positioned bars 90 secured to the under side of the bottom wall 16 of the casing 14. The ends of the supporting rod or bar project beyond the side walls 18 and the under side ends of the supporting standards are pivotally secured thereto by pivot pins 92. As seen in Figure 8, the length of the supporting standard is substantially similar to the height of the casing and tank when in closed relation. Thus, for carrying purposes, handles 94 are secured to the wall 22 and outer side wall of the casings and the supporting standards are swung about their pivots into a position encircling the casings and tank and thereby holding them in closed relation.

Means is provided for locking the standards in a lowered position and consists of lateral ends 96 formed on the legs of the standards and extending from the pivot 92, the ends being provided with upstanding angular latch elements 98. The latch elements are adapted to be vertically disposed through vertical openings 100 in the bottom wall 16 of the casing, when the standards are in vertical relation to the casing and a complementary latch member or locking bar 102 is slidably mounted within a guide housing 104 formed on the inner surface of the bottom wall 16, the guide bars 102 being disposed transversely to the openings 100. Springs 106 are connected at one end to the housing 104 and at their opposing ends to the inner end 108 of the locking bars, so that the springs 106 urge the locking bars toward the openings 100 and into latching engagement with the latch elements 98.

It can be seen that the casing 14, can thus be supported in a raised horizontal position and that the tank can be locked in right angular relation to the casing. The faucet 26 overlies the open inner wall of the casing and the heated water flowing therethrough will be directed into one of the basins or receptacles. Of course, if desired, drains could be formed in the basins and hand grips could be formed in the upper flanges thereof, in order to render the handling of the basins more convenient.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A portable sink comprising a pair of hingedly connected casings, the first of said casings being closed to form a tank, the second of said casings having an opening formed in its inner wall, means for supporting said first casing perpendicular to the second casing, and a detachable receptacle seated in the opening in the second casing, and said first casing being provided with outlet means overlying the receptacle in the second casing whereby water in the first casing can flow into the receptacle.

15 2. A portable sink comprising a pair of hingedly connected casings, the first of said casings being closed to form a tank, the second of said casings having an opening formed in its inner wall, means for supporting said first casing perpendicular to the second casing, outlet means in said first casing overlying the opening in the second casing whereby water in the first casing can flow into the opening in the second casing, and means for heating water in the first casing, said last named means including heating tubes 20 25 mounted in the first casing, a burner unit attached to the casing and disposed below the tubes.

3. A portable sink comprising a pair of hingedly connected casings, the first of said casings being closed to form a tank and cover member, the second of said casings having an opening formed in the inner wall, means for supporting said first casing perpendicular to the second casing, supporting rim means secured within said second 30 35 casing, a detachable receptacle disposed on said rim means and supported thereby, and outlet means in said first casing overlying said receptacle whereby liquid from the first casing can flow into said receptacle.

40 4. A portable sink comprising a pair of hingedly connected casings, the first of said casings being closed to form a tank and cover member, the second of said casings having an opening formed in the inner wall, means for supporting said first casing perpendicular to the second casing, supporting rim means secured within said second casing, a detachable receptacle disposed on said rim means and supported thereby, and outlet means in said first casing overlying said receptacle whereby liquid from the first casing can flow into said receptacle, said first recited means including a pair of supporting arms pivotally secured to the inner wall of said tank, said rim means being formed with openings lying in the same plane as said arms, the free ends of said arms being formed with notches for selective engagement with the edges of said openings, and stop means for limiting the pivoting movement of said tank.
